UNITED STATES PATENT OFFICE

ROYER LUCKENBACH, OF BROOKLYN, NEW YORK

AMALGAMATOR

Application filed August 23, 1928. Serial No. 301,506.

The present invention relates to devices for removing a mineral from its ore and discharging the gangue into a suitable waste outlet while retaining the mineral in its natural or treated state for further refinement or separation. More particularly, the invention relates to devices of the above character in which centrifugal force is utilized to aid in the separation, this force serving not only to separate the lighter from the heavier particles but also to cause the ore to be thrown into intimate contact with a substance which acts upon the mineral to remove it from the ore. The most common substance for performing this function is activated mercury. By reason of its great weight the mercury is thrown outwardly against vertical walls by the centrifugal force and the ore, as it is continually fed into the machine, is thrown against this wall of mercury, thus effectively exposing all surfaces of the particles of ore to the mercury to cause the latter to separate the entire mineral content from the ore.

In accordance with the foregoing, an object of this invention is to provide a device which is capable of receiving a continuous supply of mineral laden ore as well as a continuous supply of activated mercury and effecting the complete separation of the mineral from the ore as the latter passes through the device. It is contemplated that the ore will travel a circuitous route and be thrown against several batches of activated mercury in successive stages, the waste or treated substance then being discharged after its entire mineral content has been removed.

Further objects will appear as the invention is described more fully in connection with the accompanying drawing, wherein the single figure is a view in section through a device constructed in accordance with the present invention, showing the rotating element and manner of forming successive compartments for receiving the continuous ore supply and treating in successive stages.

More particularly, the device comprises an outer stationary casing α mounted upon pedestals α' . This casing is formed with inner and outer walls α^2 and α^3 , respectively. In the preferred form these walls form an an-

nular chamber α^4 with a sloping bottom α^5 . An outlet α^6 is provided at the lowest portion of the sloping bottom and the gangue is discharged at this point into a suitable conduit for carrying it away. A partition α^8 extends upwardly from the bottom of the chamber to form an inner chamber α^9 formed with a valved outlet α^{10} and a gauge α^{11} , the former serving to permit the withdrawal of the contents of the inner chamber in accordance with the conditions as indicated by the gauge.

The outer wall α^3 is formed with a flange α^7 at its top to provide a bearing for the top β of the mechanism. Wing nuts and bolts β' secure the top to the casing and a downwardly extending annular flange β^2 is formed on the top to be received in the annular chamber α^4 . This flange serves as a baffle against which the ore impinges as it flies outwardly due to centrifugal force. After striking the flange β^2 the ore falls into the annular chamber α^9 from which it overflows into the chamber α^4 .

The cover β is formed with a downwardly stepped portion β^3 from which depends a cylindrical amalgam plate β^4 , the function of which will be described hereinafter. A second stepped portion β^5 on the cover carries a depending pot β^6 . The bottom of the pot is formed with a central recess β^7 into which is threaded a fitting β^8 having an upwardly extending shoulder β^9 . The bottom of the pot contains a quantity of activated mercury β^{10} as indicated in dotted lines.

To the inner vertical wall of the second stepped portion β^5 a funnel β^{11} is secured, the restricted aperture β^{12} of which is coaxial with the aperture β^7 of the pot. A spider β^{13} supports a cylindrical container β^{14} within which a supply of activated mercury is maintained. Extending downwardly from the chamber β^{14} , pipe β^{15} passes through the apertures β^{12} and β^7 and serves to discharge a desired quantity of activated mercury, the amount of which may be controlled by a valve β^{16} which functions automatically, into the rotating element described hereinafter. A spreader disc β^{17} is mounted on the pipe β^{15} and causes the ore to be discharged adjacent

the periphery thereof. A flange b^{18} is formed at the periphery of the disc to maintain a quantity of ore and activated mercury on the disc continually, a second container b^{19} being carried by the spider to discharge a desired quantity of activated mercury upon the disc through valved pipe b^{20} . The foregoing structure, when considered with the supply pipe c for introducing the ore into the machine, comprises the stationary portion thereof. For mixing the ore and activated mercury intimately and causing the complete separation of the mineral from the ore the following rotating portion of the device is provided. Mounted upon a pedestal d through bearings d' is a rotatable plate e . This plate is directly below the pot b^6 and receives the overflow therefrom through the aperture b^7 . At the periphery of the plate, a depending annular channel e^2 is formed, the outer wall e^3 of which extends upwardly opposite the vertical wall of the pot b^6 and concentric therewith. At the top of the vertical wall e^3 , an inwardly extending radial flange e^4 is formed. As activated mercury is dropped upon the rotating plate e' , it covers the surface thereof and falls into the channel e^2 . Being very heavy, the centrifugal force causes the mercury to climb the vertical wall e^3 and form a vertical column as indicated in dotted lines at e^6 . The ore in passing through the funnel and over the distributing disc b^{17} will come into contact with the activated mercury b^{19} within the pot b^6 . It is then discharged through the aperture b^7 and falls upon the rotating plate e' . The centrifugal force imparted to the ore by the rotating plate causes the former to be thrown outwardly into the channel e^2 at which point it comes into contact with the centrifugal column of mercury e^6 . In the above described travel, the ore has, in effect, been in contact with the mercury in four different stages viz; on the disc, in the pot, upon the rotating plate, and in the channel e^2 and its vertical column of mercury e^6 . The heavier particles of ore which contain the mineral are forced outwardly to engage the mercury e^6 while the lighter particles are carried over the periphery of the radial flange e^4 . Passing over this, the ore is thrown outwardly against the stationary amalgam plate b^4 and falls into a chamber e^7 which is concentric to the amalgam plate b^4 and is formed with an annular channel e^8 , secured to the vertical wall e^3 by means of suitable flanges e^9 . The vertical wall e^{10} is formed with a T-shaped extremity e^{11} , the outer flange of which has a depending flange overlying the inner wall a^2 of the outer casing a and prevents the ore from falling through the space between the rotating and stationary members. As the ore is received in the channel e^8 , the centrifugal force imparted thereto causes it to impinge against a vertical column of mercury e^{12} , thus providing an additional stage

for removing any mineral which might be left in the ore after passing through the stages described above.

As stated in connection with the channel and vertical wall e^3 , the heavier or mineral laden particles of the ore impinge against the vertical column of activated mercury e^{12} while the lighter particles pass out over the T-shaped periphery of the wall e^{10} and impinge against the depending flange b^2 .

By means of the above described construction, the amalgam plate b^4 and additional column of mercury e^{12} provide two further stages in which the ore is brought into contact with the activated mercury to effect the complete separation of the mineral therefrom. Drain cocks f are provided at suitable points in the bottoms of the channels e^2 and e^8 and permit the withdrawal of the activated mercury which has attacked the mineral carried by the ore. This portion of the mercury is heavier than the fresh activated mercury and, accordingly collects in the bottoms of the channels. A second supply of activated mercury may be carried in a chamber g for replenishing the mercury within the channel e^8 and the entire rotatable structure is driven through a shaft h and power source h' .

For obtaining best results the ore is ground and mixed with water in order that it may readily pass through the device, the small particles of ore aiding materially in causing the mineral to be removed completely therefrom.

While the invention has been described in connection with the specific device shown in the accompanying drawing, it is understood that the specific design and construction may be altered in accordance with varying conditions and the invention is not to be limited, save as defined in the appended claims.

I claim as my invention:

1. A device for separating mineral from ore comprising means to supply ore continuously, a cylindrical chamber having a vertical wall formed with an inwardly projecting flange adjacent the top thereof, means to rotate the chamber, means to introduce the ore into the chamber, said chamber containing a medium for separating the mineral from the ore, means to remove the separated mineral, a cover for the chamber, a depending receptacle carried by the cover within the chamber and formed with an aperture adjacent the axis thereof, a funnel carried by the cover and having its mouth coaxial with the aperture in the receptacle, a spreader disc within the receptacle below the funnel and extending adjacent the internal periphery thereof, and means to supply the ore to the disc.

2. A device for separating mineral from ore comprising means to supply ore continuously, a cylindrical chamber having a vertical wall formed with an inwardly projecting flange adjacent the top thereof, means to ro-

tate the chamber, means to introduce the ore into the chamber, said chamber containing a medium for separating the mineral from the ore, means to remove the separated mineral, 5 a cover for the chamber, a depending receptacle carried by the cover within the chamber and formed with an aperture adjacent the axis thereof, a funnel carried by the cover and having its mouth coaxial with the 10 aperture in the receptacle, a spreader disc within the receptacle below the funnel and extending adjacent the internal periphery thereof, a spider carried by the cover and carrying a container for the medium, and 15 means to supply ore to the disc.

3. A device for separating mineral from ore comprising means to supply ore continuously, a cylindrical chamber having a vertical wall formed with an inwardly projecting 20 flange adjacent the top thereof, means to rotate the chamber, means to introduce the ore into the chamber, said chamber containing a medium for separating the mineral from the ore, means to remove the separated mineral, 25 a cover for the chamber, a depending receptacle carried by the cover within the chamber and formed with an aperture adjacent the axis thereof, a spider carried with the cover and carrying a container for the 30 medium, a pipe extending downwardly from the container through the aperture in the receptacle, a spreader disc mounted upon the pipe within the receptacle extending adjacent the internal periphery thereof, and 35 means to supply ore to the disc.

4. A device for separating mineral from ore comprising means to supply ore continuously, a cylindrical chamber having a vertical wall formed with an inwardly projecting 40 flange adjacent the top thereof, means to rotate the chamber, means to introduce the ore into the chamber, said chamber containing a medium for separating the mineral from the ore, means to remove the separated mineral, 45 a cover for the chamber, a depending receptacle carried by the cover within the chamber and formed with an aperture adjacent the axis thereof, an upwardly extending flange forming the aperture, a spreader disc 50 within the receptacle and extending adjacent the internal periphery thereof, and means to supply the ore to the disc.

This specification signed this 22nd day of August, A. D. 1928.

55 ROYER LUCKENBACH.
